PROCESS OF MAKING CARBURETED WATER GAS

Filed March 26, 1926

UNITED STATES PATENT OFFICE

DANIEL J. YOUNG, OF TACOMA, WASHINGTON, ASSIGNOR TO YOUNG-WHITWELL GAS PROCESS COMPANY, OF TACOMA, WASHINGTON

PROCESS OF MAKING CARBURETED WATER GAS

Application filed March 26, 1926. Serial No. 97,603.

The invention relates primarily to improvements in the process of making carbureted water gas and the present application is a continuation in part of my application, Serial No. 570,207, filed June 22, 1922 now Patent No. 1,751,849 granted March 25, 1930.

I have discovered that if the ordinary water gas process be modified, first by superheating steam or other gas, used in a back or down run, in some cases with the addition to the fuel bed, during said back or down run, of finely divided fuel which is capable on distillation of giving off condensable and non-condensable volatiles, a gas is produced which differs in character and composition from gas produced by any commercial process now known to me. These volatiles are passed through the fuel bed without material degradation, and the condensable portions may, if desired, be separated from the non-condensable portions in any suitable or known manner.

An apparatus for carrying out my process may be obtained by slightly modifying an ordinary water gas set. Such an apparatus is shown in vertical section by the accompanying drawing. In this apparatus, 1, 2 and 3 represent respectively a generator, carburetor and superheater, these being in the main the same as are now commonly used in making water gas.

The generator has the customary grate 11, an ash pit 10 to which air for the blast is applied through a pipe as 50 and steam is supplied for making gas, as through pipe 6, these being controlled by valves 51 and 60. A gas offtake pipe 7 may also be connected at the same place. A second steam pipe 61 and controlling valve 60 may be connected with the top of the generator for special uses if desired. Likewise, gas may, if desired, be removed from the top of the generator as by pipe 91. Pipes 7 and 91 may be provided

with valves as 70 and 92. Pipes for the admission of secondary air to the carburetor and superheater as 52 and 54 and controlled by the valves 53 and 55 are provided.

The carburetor 2 has the usual checker-brick 23 and chamber 20 at the bottom and the superheater 3 has its checkerbrick 33, bottom chamber 30, and stack valve 32, as is common in water gas sets. The bottom chambers 20 and 30 of carburetor and superheater are connected by a pipe 43 in the usual way. The upper ends of generator and carburetor are connected by a flue or pipe 4, which is like the connection used in ordinary water gas sets, except that the hot valve 40 and the down pipe 41 and its valve 42 connecting with the bottom of the generator employed in the usual water gas set are or may be omitted. The carburetor may have means, as pipe 21 through which oil may be supplied to enrich the water gas. The off-take for gas usual in water gas practice, as 31, may be provided with valve as 34.

In modifying a water gas set for carrying out my process, I provide means for introducing steam at the end of the set furthest removed from the generator, that is, at the point where the gas is discharged in standard water gas practice. Pipe 62 controlled by valve 60 indicates such steam supply. I have also shown a steam supply pipe 64 discharging into the bottom of the carburetor. While the location of pipe 62 is that preferred, other locations as that of pipe 64 nearer to the generator, may be employed. The essential requirement in my process is the introduction of steam for use in the back run at such a point that it has become sufficiently superheated when it reaches the generator.

I also modify the standard water gas set by providing means for introducing finely divided fuel into the generator above the fuel bed. The means indicated in the drawing is to be considered only as typical and not as the only suitable means. This shows a hopper 90

or feed bin 8, a feed screw 80 discharging into a pipe 81 which discharges into the generator and a distributing device comprising a disk 90 carried in the generator in position to receive thereon the discharge fuel and revoluble with its supporting shaft 9. There may be provided a device with which the surface of the fuel bed may be rabbled or otherwise agitated so as to permit of the ready flow through 10 of gases. The fuel supplying means illustrated are recognized as being of a rudimentary character and capable of further refinement of design.

In carrying out my process the first step is 15 a blasting operation designed to heat the checkerwork of the carburetor and superheater, just as in the standard water gas process. On the back run, steam or other gas is introduced at the discharge end of the superheater, 20 or at such point between this and the generator as will sufficiently superheat the gas by the time it reaches the generator.

I have found that passage of steam or other 25 gas through the superheater and carburetor produces a reaction upon the carbon which becomes deposited upon the walls and checkerwork, producing gaseous oxides of carbon. One beneficial result of this action is cleaning 30 the carburetor and superheater of carbon deposits. By the time the steam and gaseous oxides of carbon reach the generator they have become very highly heated. In entering 35 the generator the superheated steam and gaseous oxides of carbon may travel either one of two paths. Preferably, since the hot valve

steam to form water gas. I have found that the coke supply so produced is sufficient to supply the heat needed for superheating the steam and the water gas component of the resulting gas.

The gas which is the ultimate product of this process contains more B. t. u.'s than would a gas produced from the same fuel by any other process known to the art. The reason for this is believed to be that it contains a larger percentage of the higher hydrocarbons, of which methane and benzene are types.

That is, the process is one which does not break up and degrade these higher types of hydrocarbons, but retains them in the form as originally distilled from the fuel.

It is well known that of the higher hydrocarbons, benzene (C_6H_6), a single ring compound, when treated to $600^{\circ} C.$ condenses to solid diphenyl ($C_{12}H_{10}$), a double ring compound eliminating hydrogen gas, and when heated to higher temperature, condenser further to a triple ring compound with elimination of more hydrogen until ultimately only solid carbon remains. These reactions may be indicated as follows:—

(1)

(Double bonds are omitted from ring.)

40

45 40 and the connections thereto may thereby be eliminated, they enter the top of the generator, have mixed with them the finely divided fuel supplied through pipe 81 and pass downwardly through the fuel bed. As an alternative, however, by employing down pipe 41 and valves 40 and 42, the steam and gaseous oxides of carbon thus superheated may be caused to pass up through the fuel bed, produce water gas and leave the set by pipe 91. 50 Fuel may be added during this operation. This fuel for best results should be finely divided. It should also contain volatile hydrocarbons, distillable under heat to form gases.

55 If the added fuel be finely divided it absorbs heat from the superheated steam, water gas and gaseous oxides of carbon received from the carburetor, giving off the volatile components as gas and depositing the remainder as coke upon the fuel bed, except that 60 portion which may combine with the excess

If, however, hydrogen and, to a less extent any other diluting gas, as nitrogen, steam, carbon dioxide, etc., be present the above described decomposition or dehydrogenation is practically nullified up to a temperature of at least $800^{\circ} C.$ These or any other gases, may be substituted for the steam in the "back run".

65 It is also well known that, of the hydrocarbons, toluene (C_6H_5, CH_3), a single ring compound when heated to $600^{\circ} C.$ condensed to such compounds as solid stilbene ($C_{14}H_{12}$), a double ring compound, eliminating hydrogen gas. At higher temperatures ($800^{\circ} C.$) there is further condensation, the nucleus (C_6H_5), giving anthracene ($C_{14}H_{10}$) with elimination of hydrogen gas, the latter, however, reacting further with toluene to give benzene and methane (CH_4). At still higher temperatures the nucleus condenses further

115

135

and ultimately yields solid carbon. These reactions may be indicated as follows:—

(Double bonds are omitted from rings. Reversibility shown
thus $\rightleftharpoons$ only where established.)

If, then, a large quantity of hydrogen is present initially, the action is checked as shown in connection with the formation of diphenyl from benzene. The hydrogen can, however, act directly on the toluene, reducing it to benzene by combining with the CH_3 group to form methane. Although the presence of hydrogen lessens the formation of solid molecular condensates, it promotes the decomposition of toluene by reduction to benzene, from whence the other reactions involving the latter occur. Diluting gases, other than hydrogen, would act, in some cases, to retard toluene decomposition and, in others, to lessen the degradation of benzene, after the latter has been formed.

In like manner, the three zylenes, ortho-, meta- and para-, yield, in an atmosphere of hydrogen at 750°C . toluene and benzene by reduction and a limited amount of solid condensates. Cresol, is also reduced extensively at 750°C . in a stream of hydrogen to toluene and necessarily to benzene also.

Finally, it is also well known that all chemical equilibria require time for their complete establishment. Methane, for example, when hydrogen is present becomes increasingly unstable as the temperature rises, so that, at the temperatures prevailing in the carbonization system, the tendency of reaction is all in favor of the destruction of methane. Yet the decomposition occurs sufficiently slowly that, if means be provided for removing the methane from the zone of reaction, such decomposition is noticeably retarded. Any gas sweeping through the reaction zone will so retard degradation by removal of the decomposing gas. Hydrogen is particularly effective in this respect, not only because its action is chiefly chemical, but also because of its lightness, its

diffusive power and the speed with which its molecules travel. An inert or non-oxidizing

70

gas, as nitrogen, is also effective by reason of its distilling action for it can physically sweep out the forming and reacting gases from the pores of the fuel, and so remove them from the zone of degradation. Particularly is this true if the fuel be in a state of fine division.

Where combustible gas is desired, the nitrogen may be supplied by admitting air into the system and passing it over the heated checkerbrick and through the fuel bed of the generator. The oxygen in the air will be largely converted into gaseous oxides of carbon by reaction with the carbon upon the checkerbrick, and these gases, together with the nitrogen passing through the fuel bed of the generator, sweep out and carry with them the forming and reacting gases contained in the pores of the fuel in the manner described above. Where fuel distillation is the primary object, nitrogen substantially free from oxygen may be employed instead of air.

With proper regulation of conditions large quantities of ammonia can be recovered by means of this process as where steam and a nitrogen containing gas are admitted together during the "backrun".

In summation, therefore, it may be said the dehydrogenation with resulting solid condensates and degradation of the nucleus at high temperatures is noticeably retarded, in the presence of any gas stream, the action being chemical or physical or both and particularly effective when fine division of the fuel permits of intimate contact between the gas stream and solid fuel particles.

In my process, therefore, by reason of the volumes of steam, water gas and other constituents of the gas stream which is flowing through the zone of distillation and through the fuel bed, degradation of higher hydrocarbons in the distillation gases is retarded. Such retardation of degradation is due, in part, to the presence of hydrogen or other gases, not only in the distillation gases themselves but also in the forming of water gas. Degradation of such higher hydrocarbons is further retarded because the distillation gases are quickly removed from the pores of the finely divided fuel and from the high temperature zone thereby materially shortening the time during which they are exposed to the breaking down tendency of such high temperatures. In consequence, the gas produced has a higher percentage of the higher hydrocarbons than the gases of analogous

character heretofore commercially produced. The condensable portions of such gas may, if desired, be separated out in any suitable manner.

5 As these gases pass through the fuel bed the excess steam contained therein combines with the carbon to form water gas. There may also be interaction between the gases distilled from the raw fuel and the carbon 10 of the fuel bed. There is less free hydrogen in the final gas as there is less breaking down of the higher hydrocarbons.

Obviously, the process is not confined to gas manufacture, but is applicable generally to 15 distillation and carbonizing processes, and may be used for the extraction of volatiles from oil shale. The "backrun" principle is also applicable to ammonia recovery and like processes.

20 While the terms "carburetor" and "superheater" are used throughout the specification as referring to the shells 2 and 3, the terms "primary" and "secondary heat interchangers" may be used to refer to the same elements.

25 Having thus described my invention, what I claim as new and desire to secure by Letters Patent is:—

1. An improvement in the usual two-cycle process of making carbureted water gas, carried out in a plant comprising a single generator having a bed of solid fuel, a single carburetor and a single superheater, one cycle consisting in air blasting the fuel bed of the generator and storing the resulting heat successively in the carburetor and superheater, and the other cycle consisting in making a forward steam run through the fuel bed in the generator in an upward direction, then passing the generated water gas through the carburetor and superheater, simultaneously adding oil to the carburetor and withdrawing the resultant carbureted water gas directly from the superheater; the improvement which consists in introducing nitrogen into 35 the plant, superheating the nitrogen and passing it in a downward direction through the fuel bed of the generator, whereby a combustible gas is produced, and withdrawing the resulting combustible gas directly from the generator.

2. An improvement in the usual two-cycle process of making carbureted water gas, carried out in a plant comprising a single generator having a bed of solid fuel, a single carburetor and a single superheater, one cycle consisting in air blasting the fuel bed of the generator and storing the resulting heat successively in the carburetor and superheater, and the other cycle consisting in making a forward steam run through the fuel bed in the generator in an upward direction, then passing the generated water gas through the carburetor and superheater, simultaneously adding oil to the carburetor and withdrawing the resultant carbureted water gas

directly from the superheater; the improvement which comprises introducing a gas having a large nitrogen content into the plant, superheating the nitrogen and passing it through the fuel bed of the generator, whereby combustible gas is produced, and withdrawing the resulting combustible gas directly from the generator. 70

3. An improvement in the manufacture of carbureted water gas, carried out in a plant comprising a single generator having a bed of solid incandescent fuel, a single carburetor and a single superheater; which improvement comprises the step of introducing nitrogen into the plant, superheating the nitrogen within the plant, mingling said superheated nitrogen with finely divided fuel containing volatiles, extracting said volatiles, passing the nitrogen and volatiles through the incandescent fuel bed of the generator, and withdrawing the resulting gaseous product directly from the generator. 75

4. An improvement in the manufacture of carbureted water gas, carried out in a plant comprising a single generator having a bed of solid incandescent fuel, a single carburetor and a single superheater; which improvement comprises the step of introducing a gas having a large nitrogen content into the plant, superheating the gas within the plant, 80 mingling said superheated gas with finely divided fuel containing volatiles, extracting said volatiles, passing the gas and volatiles through the incandescent fuel bed of the generator, and withdrawing the resulting gaseous product directly from the generator. 85

5. An improvement in the manufacture of carbureted water gas, carried out in a plant comprising a single generator having a bed of solid incandescent fuel, a single carburetor and a single superheater; which improvement comprises the step of introducing a gas having a large nitrogen content into the plant, superheating the gas and passing it through the fuel bed of the generator, whereby combustible gas is produced, and withdrawing the resulting combustible gas directly from the generator. 95

In testimony whereof I affix my signature.
DANIEL J. YOUNG. 115
